ALFRED C. GOETHEL, OF MILWAUKEE, WISCONSIN

FUMEPREOF SPRAY CABINET

Application filed June 28, 1926. Serial No. 119,041.

This invention relates to improvements in fume proof spray cabinets.

Such cabinets are usually provided with powerful air drafts which not only interfere with the application of the spray by the operator, but also subject the operator to considerable inconvenience, annoyance, and, at times, to danger from chilling drafts. It has also been found that the use of powerful air currents carry away large quantities of the material during painting, varnishing, or other spraying operations, and are frequently ineffective to fully accomplish the object of protecting the workmen from the fumes and rebounding atoms of poisonous or deleterious substances.

The object of this invention is to provide a cabinet having an open side protected by an effective air curtain between the position occupied by the operator and the object to be sprayed.

A further object is to provide means, whereby such an air curtain can be produced by air currents having minimum volume and pressure or velocity, whereby materials heavier than the air may be permitted to pass by gravity to the bottom of the cabinet, and whereby workmen may be protected with minimum inconvenience and maximum security.

A further object of the invention is to provide means, whereby air under pressure slightly greater than that in the atmosphere, may be delivered in the form of converging sheets across a cabinet opening and withdrawn by suction induced by an ejector air current in an exhaust passage, thereby avoiding the use of suction fans for exhausting air from the cabinet and avoiding the use of any other movable parts in the exhaust passage which might become clogged by materials condensed or precipitated from the outgoing air.

In the drawings:

Figure 1 is a vertical sectional view of the improved cabinet, drawn to a central plane, which includes the axis of the exhaust passage.

Figure 2 is a cross sectional view of one of

the slotted tubes employed for producing the air curtain, the section being taken on line 2-2 of Figure 1.

Figure 3 is a fragmentary view of one of said slotted tubes, showing a portion of the inlet pipe and controlling valve.

Figure 4 is a front elevation of the improved cabinet.

Figure 5 is a sectional view of portions of the baffle curtains, drawn on line 5-5 of Figure 4.

Like parts are identified by the same reference characters throughout the several views.

The improved cabinet has a top wall 10 which is provided with apertures near the front corners through which air supply pipes 11 extend, these pipes being elbowed above the top wall and connected with an air supply main 12 leading from any suitable source, such as a fan or pump. The front of the cabinet is open except along the margins and side walls, which are preferably provided with inturned flanges 13, which may comprise portions of corner pieces, or angle pieces, secured to the margins of these walls. In each front corner of the space enclosed by the walls of the cabinet, a substantially vertically disposed, slotted tube 15 is connected to one of the pipes 11 and has a closed lower end which is preferably tapered as indicated at 16 and seated in a cup shaped or tapered bearing 17 secured to the bottom wall 18 or beam 19 of the cabinet. Each tube 15 is not only provided with a longitudinal slot 20, but the side margins of this slot are flanked by outwardly projecting flanges 21 which form what may be termed "a nozzle slot" through which a sheet of air may flow, the dimensions of which from top to bottom are substantially equal to the vertical dimension of the opening at the front of the cabinet. The slotted tube 15 has its upper end rotatably seated over the lower end of the supply pipe or duct 11 so that by rotating the tube 15, the air may be directed through the slot at the desired pitch or angle of divergence from the plane of the opening in the front of the cabinet.

100

The opening at the front of the cabinet is flanked on each side by a pair of vertical tubes 15 and a similar slotted tube 25 extends across the cabinet at a short distance below the top wall and is provided with a downwardly directed slot nozzle 26. At one end, this pipe is also journalled upon the horizontally disposed extremity of a supply pipe 27 leading from the main 12 downwardly through an aperture in said top wall, with another elbow 28 within the cabinet, as clearly shown in Figure 4.

At the rear, the cabinet is provided with rearwardly converging back walls 30 leading 15 to an outlet aperture 31 with which a stack or outlet flue 32 is connected. An induced draft is preferably promoted in this outlet flue by means of a pipe 33 leading from the main 12 into the flue and provided with an 20 upturned elbowed portion 34. The lower portion of the flue is large enough to allow for the space occupied by the ejector pipe 33 so that this pipe offers no material obstruction to the flow of air outwardly through the 25 flue. Baffle curtains are preferably suspended in the rear portion of the cabinet to prevent particles of the sprayed material from being carried by the air into the outlet flue to any great extent. These baffles are 30 preferably formed of thin sheet metal channel bars 35, those in the rear curtain being staggered with reference to those in the front curtain, whereby the air strikes the baffles and is deflected in order to pass between those 35 of the front curtain and those of the rear curtain, as indicated by the arrows in Figure 5. These baffles are preferably suspended from the upper portion of the back wall by means of suitable brackets 37. The side walls of 40 the cabinet may be provided with openings which are normally closed by slides or doors 39.

In order to control the quantity of air to be delivered to the respective slotted tubes 15 and 25 and through the ejector tube 33, each of the tubes 11, 27 and 33 is provided 45 with a gate valve 40 which may be opened or closed to a desired extent to regulate the proportionate quantity of air to be delivered 50 through the tube.

The mode of operation of the improved fume proof cabinet may be briefly summarized as follows: The object to be painted, varnished, or otherwise sprayed, will be 55 placed within the cabinet in front of the baffles 35, and the slotted nozzle tubes will be adjusted for delivery of three sheets of air across the cabinet in front of the object, two of these sheets coming from the tubes 60 15 at the respective sides near the front corners and the third sheet coming from the top. The tubes will preferably be adjusted in such a manner that the sheets of air will converge toward a point or area in front of 65 the object. The upper portions of the air

currents from the tubes 15 will of course intersect portions of the sheet of air delivered from the upper tube 25, but this intersection will occur near the side walls of the cabinet and the resulting deflections will be downwardly and toward the center, thereby increasing the thickness of the air current in front of the object to be sprayed. The entire body of air will of course move rearwardly along oblique lines and will eventually pass 75 the object in the direction of the outlet 31, the capacity of which is such as to provide for a withdrawal of all of the air which passes through the tubes 15 and 25, together with some additional air entering the cabinet 80 through the open front. I have discovered that these obliquely moving sheets of air form a curtain which effectively intercepts and deflects all rebounding particles and 85 reversely moving fume carrying currents, whereas air currents moving directly from front to rear frequently develop counteracting currents by contact with the rear walls and baffles and these tend to carry the fumes and entrained particles of poisonous material outwardly through the front of the cabinet. I have also discovered that these low 90 velocity oblique currents, delivered in the form of sheets of converging air in the direction of an outlet through which air is 95 being exhausted under light suction, not only deflect rebounding particles and eddies, but that they also tend to progressively neutralize each other as to initial direction and combine to form a continuously flowing 100 steady current of air passing outwardly through the exhaust flue.

I claim:

1. The combination of a spray cabinet provided with an opening flanked by slotted tubes at the sides and top thereof, means for delivering air under pressure to said slotted tubes, means for adjusting said tubes to direct the air through said slots in inwardly converging sheets, and means for withdrawing air from the side of the cabinet toward which said sheets of air converge. 110

2. The combination of a spray cabinet provided with an opening flanked by slotted tubes at the sides and top thereof, means for delivering air under pressure to said slotted tubes, means for adjusting said tubes to direct the air through said slots in inwardly converging sheets, valves for separately controlling air delivery to the respective tubes, and means for withdrawing air from the side of the cabinet toward which said sheets of air converge. 115

3. The combination of a spray cabinet provided with an opening in its front wall flanked by axially adjustable slotted tubes, air directing flanges extending outwardly from said tubes along the side margins of the slots therein, and means for supplying air under pressure to said tubes in independently 120

controlled volume, each of said tubes being rotatably adjustable to regulate the pitch of the air current delivered through its slot, said cabinet having an outlet on the side opposite said tubes.

4. The combination of a spray cabinet provided with a main for supplying air under pressure, of a set of branch pipes leading from said main downwardly and through the walls of the cabinet near the front upper corners thereof, vertically extending slotted tubes rotatably embracing the delivery ends of some of said pipes, and a horizontally extending slotted tube rotatably embracing the delivery end of another of said pipes, said last mentioned pipe having a horizontally disposed extremity, said cabinet having an opening in its front wall flanked by said tubes at the sides and top and said tubes being rotatably adjustable to direct sheets of air convergingly toward the central portion of the cabinet.

5. In a spray cabinet having an open front and an outlet, the combination with air delivery tubes upon opposite sides of said open front adapted to deliver air across said opening, of an ejector in operative relation to said outlet, an air supply main connected with each of said tubes and with said ejector, and means for controlling the flow of air from said supply main to each of said tubes and said ejector independently to substantially balance the volume of air discharged into and withdrawn from the cabinet.

35 6. In a spray cabinet having an open front and an outlet, the combination of means for passing air through said cabinet in substantial absence of in-draft through said open front, said means comprising perforated conduit means adapted to discharge sheet-like streams of air across said open front, air supply means for said conduit means, said air supply means having an intake remote from said open front, and means for drawing the air through said outlet at substantially the rate of discharge in the cabinet and discharging it at a point remote from both said intake and said open front.

ALFRED C. GOETHEL.
